ICE BUCKET

Manuel S. Ziskin, Mayfield Heights, and Ralph B. Billig,
Willoughby, Ohio, assignors to Kromex Corporation,
Cleveland, Ohio, a corporation of Ohio

Application February 19, 1954, Serial No. 29,121

Term of patent 14 years

(Cl. D44—1)

FIG. 1

FIG. 2

FIG. 3

Fig. 1 is a top plan view of an ice bucket, embodying our new design;

Fig. 2 is a front elevational view, and

Fig. 3 is a side elevational view of the ice bucket.

We claim:

The ornamental design for an ice bucket, substantially as shown.
